UNITED STATES PATENT OFFICE.

NELSON WATTS, OF DENVER, COLORADO, ASSIGNOR OF TWO-THIRDS TO
ROBERT S. PLATT, OF SAME PLACE.

PARLOR COOK-STOVE.

SPECIFICATION forming part of Letters Patent No. 259,249, dated June 6, 1882.

Application filed December 18, 1880. (No model.)

To all whom it may concern:

Be it known that I, NELSON WATTS, a citizen of the United States, residing at Denver, in the county of Arapahoe and State of Colorado, have invented certain new and useful Improvements in Parlor Cook-Stoves; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

My invention relates to certain improvements in parlor cook-stoves; and the novelty consists in the construction and arrangement of parts in relation to each other, as will be more fully hereinafter set forth, and specifically pointed out in the claims.

20 The object of the invention is essentially to combine a parlor-stove with an efficient cook-stove in such a manner that while the device is useful as a cook-stove it is ornamental as a parlor-stove; to carry off with the products of combustion all aroma arising from cooking edibles, or other noxious vapors; to provide an oven which, in connection with a peculiar damper, will utilize the heat arising from the combustion of the fuel, or not, at the will of 25 the attendant; to provide for ventilating a parlor by a pipe or pipes which, by the heat of the stove, will attract the impurities of the atmosphere in the room—such as carbonic-acid gas—and convey them to the flue, where they 30 are consumed; and in certain advantages of construction.

In the accompanying drawings, which form a part of this specification, Figure 1 represents a vertical longitudinal central section, 40 illustrative of the main features of my device; Fig. 2, a side elevation, the dotted lines showing the vapor-flues; and Fig. 3 is a detail plan view of the vapor-flues and their relation with the main flue or chimney-pipe. Fig. 4 is a vertical transverse section of the stove.

Referring to the drawings, similar letters of reference indicate like parts in all the figures.

A represents the stove proper, having a firebox or combustion-chamber, A', a pivoted-

weighted grate, a hinged door, a³, to admit 50 the fuel, an ash-pan, a', beneath the hearth a², and readily removable at will. A plate, B, extends backward horizontally to form between said plate and the top B' of the stove proper a combustion-flue, b', which, by proper manipulation of a damper, connects with a return-flue, b, formed between the top of the oven and the said plate B, and this flue extends entirely around the oven C and terminates in the main flue D in the chamber d.

55 The damper is of peculiar construction, is pivoted at c, and consists essentially of two approximately semicircular curves in one direction with an intervening curve in the opposite direction. As shown in Fig. 1, the heat 65 is deflected around the oven, and the ends of the damper impinge upon the point c' and the point of junction of flue and top. When the damper is turned properly the return-flue b is closed, as seen in broken lines at e in Fig. 1, 70 and a free draft is open to the chimney or main flue from flue b'.

E' represents a dome, which is of double construction to form an intervening chamber, e, and which dome entirely covers the top of 75 the stove and the cooking-vessels thereon, so that any effluvia or vapor arising from the cooking edibles will be conveyed to the flue D through the pipes H and H' and prevent its escaping into the room. This dome has proper 80 doors, and a shelf or shelves, G, for edibles, plates, or the like. The chamber e, which is shown in the sections, surrounds the stove proper on the top, rear end, and sides for the purpose of confining, in a measure, much of the 85 heat of the stove, and by means of the connection with the smoke-pipe D to carry away the heated air when the stove is used for cooking in warm weather. In cold weather the openings to D may be closed and the hot air 90 utilized for the benefit of the room.

I represents a pipe or flue situated between the casing E and the stove-side opposite the side which has the oven-door. The lower end of tube I communicates with the outer air by 95 the orifice i, Fig. 2, and this can be closed by the cap i'. The function of tube I is to draw from the room any noxious gases which by

their gravity may collect near the floor. The tube I at its upper end is connected to the tube H', which latter tube enters the smoke-pipe D at i", Fig. 3. There is also a tube, I', connected to I and opening into the oven C near the top, the purpose of which is to carry off to the smoke-pipe D any effluvia from the oven, which action can be increased by closing the outside orifice, i.

10 H is a pipe from the dome, which enters H', as before described. Through these tubes there is a draft into the smoke-pipe D.

15 F represents a hinged door in the combustion-chamber, through which the top of the oven may be cleaned of soot; and f, a door to clean the bottom flue, b.

From the foregoing description the operation of my device is obvious.

What I claim, and desire to secure by Letters Patent, is—

20 1. The combination of the cook-stove A, as shown, with the case E, dome E', and vent-tubes H H', as and for the purposes specified.

2. The dome E', vent-tubes H H', and vapor-tube I i, in combination with the flue D, as set 25 forth, for the purposes specified.

3. In cooking-stoves, the combination of the pipes or flues I i, I', H', and H, the dome over the stove, and the smoke flue or pipe D, substantially as and for the purpose described.

30 In testimony whereof I affix my signature in presence of two witnesses.

NELSON WATTS.
